UNITED STATES PATENT OFFICE.

NILS FREDERICK AMBURSEN, OF NEWTON, MASSACHUSETTS, ASSIGNOR TO THE UNI-FORM COMPANY, OF BOSTON, MASSACHUSETTS, A CORPORATION OF MASSACHUSETTS.

APPARATUS FOR CONSTRUCTING CONCRETE FLOORS.

1,278,086.

Specification of Letters Patent. Patented Sept. 10, 1918.

Application filed August 28, 1917. Serial No. 188,689.

To all whom it may concern:

Be it known that I, NILS FREDERICK AMBURSEN, citizen of the United States, and a resident of Newton, in the county of Middlesex and State of Massachusetts, have invented a new and useful Improvement in Apparatus for Constructing Concrete Floors, of which the following is a specification.

10 The principal objects of the present invention which is an improvement on the apparatus for constructing concrete floors described in my United States Letters Patent No. 1,216,644 dated February 20, 1917

15 are to provide means whereby two or more concrete forms can be used for the construction of molded concrete floors of greater span than the combined length of said forms, and to provide means whereby the 20 forms can be removed for immediate use elsewhere before the concrete has thoroughly hardened without injury to the molded structure.

With these and other objects in view my 25 invention comprises longitudinally-spaced concrete forms of any suitable construction, such for example as the wooden forms now in general use for molding concrete floors, and a bridging-member, which may be a 30 plate of any suitable material, spanning the space between said forms and overlapping the ends thereof, together with false-work having removable support-pieces arranged beneath the bridging-member and the ends 35 of said forms and so constructed that the pieces upon which the forms rest, and the forms themselves, may be removed when the concrete has sufficiently set but before it has thoroughly hardened, leaving the molded 40 structure sustained by the bridging-member and the false-work under it.

My invention comprises also the use of longitudinally-spaced concrete-form support-members, which may be channel-irons 45 as described in my Letters Patent aforesaid, concrete forms, such for example as the metallic arch-plates shown in said Letters Patent, said arch-plates spanning the space between the support-members and having 50 their lower edges resting on the webs thereof, a bridging-member which may be a sheet-metal channel arranged between the support-members and overlapping the ends 55 thereof, and a cover-plate bridging the

forms and overlapping the ends of the same, 55 together with false-work having removable support-pieces arranged beneath the bridging-member and the ends of said support members, so that said support-members and the forms which rest upon the same may be 60 removed before the concrete has thoroughly hardened.

My invention further comprises the parts and combinations of parts set forth in the appended claims.

65 My invention may best be understood by having reference to the illustrative embodiments thereof shown in the accompanying drawings wherein—

Figure 1 is an elevation showing the false-work supporting two channel-irons and a bridging-member. Fig. 2 is a plan view showing the forms in position before the concrete has been poured. Fig. 3 is a section taken on line 3—3 of Fig. 2. Fig. 4 75 is a longitudinal section on the line 4—4 of Fig. 2. Fig. 5 is a transverse section on the line 5—5 of Fig. 4. Fig. 6 is a fragmentary perspective view of one form of bridging-member that may be used. Fig. 7 is an elevation showing the false-work supporting two wooden forms and a bridging-member.

80 In the particular drawings selected for more fully disclosing my invention 1, 1', 2, 2' are light channel-irons such as described in my Letters Patent above referred to, with the exception that each channel is shorter than the distance which the floor is intended to span. The channels or concrete form support-members of whatever type employed are temporarily supported on the stringers 3, 4 arranged beneath the ends thereof and said stringers in turn are supported by a post 5 having a cap 6 or other suitable supporting means, adjusting members such as the wedges 7, 8 being interposed between the stringers and the cap for the purpose of regulating the positions of said stringers. The bridging-member 9 85 preferably a thin sheet metal channel having flanges 9' is arranged between the channels or form supporting-members and overlaps the ends thereof so that thereby the span is completed. For example I may use channels six, eight and ten feet in length 100 and bridging-members two feet six inches long, and by appropriate combinations of two channels and a bridging-member or

three channels and two bridging-members, I may complete any desired span from twelve to thirty feet. If the span is to be seventeen feet I would use two eight foot 5 channels bridged by a member 9, if twenty feet is to be spanned I would use a ten foot channel, an eight foot channel and a bridging-member, etc.

Coöoperating with each bridging-member 10 is a stringer 10 resting on adjusting means such as the wedges 11 which in turn are supported by the cap 6 whereby the channels and the forms supported thereby may be removed before the concrete has thoroughly hardened without disturbing the false-work as hereinafter more fully described.

Spanning the space between the members of each pair of channels 1, 1' or 2, 2' is a 20 concrete form herein shown as a metallic arch-plate 12 and illustrated as of angular conformation although as will readily be understood it may be curved in the manner shown in said patent. The lower edges of 25 each arch-plate rest on the webs of a pair of adjacent channels and are arranged against the juxtaposed flanges 13, 13' of the same. In order to complete the mold I employ cover-plates 15 arranged between two adjacent 30 arch-plates such as 12, 12' and overlapping the ends thereof, the lower edges of said cover-plates resting on the webs of two pairs of channels, for example, the pair 1, 1' and the pair 2, 2', the members of each of said 35 pairs of channels being spaced laterally and the pairs themselves being longitudinally separated, and said lower edges of each cover-plate being arranged against the juxtaposed flanges of two adjacent bridging-members, such as the members 9, 9'. 40

In order to clamp the arch-plates, cover-plates and bridging-members in position, the webs of the channels may be apertured at suitable intervals to receive the bolts 45 16 which pass through the clamps 17 arranged transversely of the channels. When the parts are arranged as above described with the lower ends of the arch-plates against the juxtaposed flanges 13, 14 of a channel, the 50 flanges 9' of the bridging-member being against the adjacent lower ends of a pair of arch-plates and the lower ends of the cover-plates resting against said flanges of said bridging-member, they are secured in position 55 by tightening the nut 18.

Unless the cover-plates fit tightly over the arch-plates the under surface of the floor will not be smooth and therefore I prefer to employ means clamping or otherwise securing 60 the cover-plates to the arch-plates. In the present instance I have shown a clamp bar 19 of wood, iron or other suitable material arranged under each cover-plate with its ends underlying the ends of the two adjacent arch-plates and a bolt 20 passing

through the cover-plate and clamp bar so that by means of the nut 21 the cover-plate may be securely clamped down on the arch plates which it bridges. This construction is desirable because it would not be practicable to clamp a cover plate directly to the arch-plates by means of bolts passing through both members, for, as above set forth, various combinations of channels and bridging-members are employed for spans of 75 various lengths so that the amount of overlapping of the arch and cover-plates differs in various cases and therefore holes bored through the arch and cover-plates for receiving clamping bolts would not always be 80 in register.

The concrete is poured in the mold formed as above set forth and allowed to harden, and after it has thoroughly set but before it has completely hardened, the stringers 3, 4 85 are knocked out and the channels and arch-plates removed for immediate use elsewhere, the molded floor being sustained by the stringer 10 which as above set forth is placed under the bridging member. Heretofore, 90 so far as I am advised, it is customary to remove all the false-work to release the forms as soon as the concrete has set and before it has thoroughly hardened and then to replace said false-work which is left in 95 position until the concrete has hardened or the building is completed. It will therefore be seen that by the apparatus above described I can save considerable time and labor.

It will be understood of course that the wedges 7, 8 and 11 which are used for lining up the channels and bridging-members permit the ready release of the stringers without injury to the posts and caps, and that in 105 the case of a molded roof said wedges will give the channels and bridging-members the proper slant.

It will be readily understood that my invention is not limited to use with metallic 110 concrete forms and that the construction shown in Fig. 1 may be employed with the wooden forms now generally in use without sacrificing the advantages above described. In Fig. 7 I have shown the application of 115 my invention to a case where wooden forms are employed. In this figure 22, 22' represent such forms and 23 is a bridging-member which may be a plate of iron or other material, or a plank, arranged between the forms 120 and overlapping the ends thereof. The ends of the forms rest on the stringers 24, 25, respectively and the latter are supported by the cap 6, the wedges 26, 27 or other position adjusting members being interposed respectively between the stringers and the cap. The stringer 28 which rests on the wedges 29 125 is placed beneath the bridging-member, so that, in a manner which will be clearly understood in view of the description of 130

Fig. 1, the molded structure may be supported by said stringer and the false-work after the other stringers have been removed to release the forms before the concrete has 5 thoroughly hardened.

Preferably the width of each arch-plate at its base should be less than the distance between the inner faces of the juxtaposed flanges 13, 13' of a pair of adjacent channels 10 so that it will have to be sprung out into position between said channels and will thereby be placed under a certain amount of tension until the channels are removed which is accomplished by unscrewing the 15 bolt 16 and knocking out the stringers 3 and 4 as aforesaid, whereupon the elasticity of the arch-plates will cause them to spring back from the molded concrete, or at least permit their ready removal from the same. 20 The nut 21 must, of course, be unscrewed to release the clamping bar 19 before the arch-plates can be taken down.

It will be understood that various modifications may be made in the particular apparatus above described without departing 25 from the principle of my invention.

Having thus described illustrative embodiments of my invention without however limiting the same thereto, what I claim and 30 desire to secure by Letters Patent of the United States is:—

1. Apparatus for constructing concrete floors, comprising in combination two pairs of channels spaced longitudinally, the members of each pair being spaced laterally, a pair of bridging-members arranged between said pairs of channels and overlapping the ends of the respective members thereof, metallic arch-plates spanning the members of 40 each pair of channels, and a cover-plate arranged between said arch-plates and overlapping the ends thereof and also engaging the bridging members.

2. Apparatus for constructing concrete 45 floors, comprising in combination two longitudinally-spaced support-members for concrete forms, a bridging-member arranged between said support-members and overlapping the ends thereof, false-work arranged 50 beneath said bridging-member and the ends of said support-members, and removable support-pieces placed on said false-work and coöperating respectively with said bridging member and with the ends of said support-members.

3. Apparatus for constructing concrete 60 floors, comprising in combination two pairs of longitudinally-spaced concrete-form support-members, the elements of each pair being spaced laterally, a pair of bridging-members arranged between said pairs of support-members and overlapping the ends of the respective elements thereof, concrete forms resting upon each pair of support-members, and a bridging-form arranged between said

concrete forms and overlapping the ends thereof and also engaging the bridging members.

4. Apparatus for constructing concrete floors, comprising in combination two longitudinally-spaced channels, a bridging-member arranged between said channels and overlapping the ends thereof, false-work arranged beneath said bridging-member and the ends of said channels, and removable support-pieces placed on said false-work and coöperating respectively with said bridging member and with the ends of said channels. 70

5. Apparatus for constructing concrete floors, comprising in combination two pairs of channels spaced longitudinally, the members of each pair being spaced laterally, a pair of bridging-members arranged between said pairs of channels and overlapping the ends of the respective members thereof, metallic arch-plates spanning the members of each pair of channels, a cover-plate arranged between said arch-plates and overlapping the ends thereof and also engaging the bridging member, and means securing said 80 cover-plate to said arch-plates. 85

6. Apparatus for constructing concrete floors, comprising in combination two pairs of longitudinally-spaced concrete-form support-members, the elements of each pair being spaced laterally, a pair of bridging-members arranged between said pairs of support-members and overlapping the ends of the respective elements thereof, concrete forms resting upon each pair of support-members, a bridging-form arranged between said concrete forms and overlapping the ends thereof and also engaging the bridging member, and means securing said bridging-form to said concrete form. 95 100 105

7. Apparatus for constructing concrete floors, comprising in combination two longitudinally-separated channels, a bridging-member arranged between said channels and overlapping the ends thereof, false-work arranged beneath said bridging-member and the ends of said channels, removable support-pieces placed on said false-work and coöperating respectively with said bridging-member and with the ends of said support-members, and adjusting means for regulating the positions of said support-pieces respectively. 110 115

8. Apparatus for constructing concrete floors, comprising in combination pairs of 120 channels spaced longitudinally, the members of each pair being spaced laterally, metallic arch-plates each having its lower edges resting on the webs of a pair of adjacent channels and arranged against the juxtaposed flanges thereof, a pair of bridging-members arranged between each pair of channels and overlapping the ends of the respective members thereof, said bridging-members being channel-shaped and each having its flanges 125 130

arranged against the adjacent lower edges of a pair of arch-plates, cover-plates each arranged between two adjacent arch-plates and overlapping the ends thereof, the lower edges of said cover-plates resting on the webs of two pairs of channels and against the juxtaposed flanges of two adjacent bridging-members, and means for clamping the flanges of each bridging-member and the adjacent lower edges of each pair of arch-plates and cover-plates to the flanges of a channel.

9. Apparatus for constructing concrete

floors, comprising in combination two longitudinally-spaced concrete forms, a cover-plate arranged between said forms and overlapping the ends thereof, a clamping member arranged beneath said cover-plate and having its ends underlying the ends of said forms, and means temporarily securing said member to said cover-plate. 15

In testimony whereof, I have hereunto subscribed my name this 27th day of August, 1917.

NILS FREDERICK AMBURSEN.
